TUBULAR LAMP FIXTURE

Adolf G. Mueller, Fairfield, and Frederick C. Dazley, Stratford, Conn., assignors to General Electric Company, a corporation of New York

Application November 6, 1944, Serial No. 562,082

5 Claims. (Cl. 173—328)

The present invention relates to fixtures for tubular lamps such as fluorescent lamps.

The object of the invention is to provide an improved fixture for supporting tubular lamps and an improved lamp holder for use in tubular lamp fixtures, and for a consideration of what we believe to be novel and our invention attention is directed to the following specification and to the claims appended thereto.

In the present instance, the invention is shown as embodied in a fixture for two lamps but it will be understood that the invention is not limited necessarily to a two-lamp fixture, as it may be utilized in a fixture for only one lamp or in a fixture for more than two lamps.

In the drawings Fig. 1 is a perspective view of a lamp fixture embodying the invention; Fig. 2 is a perspective view on a larger scale, partly broken away and partly in section, of the fixture shown in Fig. 1; Fig. 3 is a face view looking at the underside of the fixture, the central portion of the fixture being broken away and certain parts being shown in section; Fig. 4 is an exploded perspective view of parts which go to make up a lamp holder; Fig. 5 is a transverse sectional view of the fixture looking toward one of the lamp holders; Fig. 6 is a detail sectional view through one of the lamp holders taken on line 6—6, Fig. 3; and Fig. 7 is a detail perspective view partly broken away of a modification.

Referring to the drawings, the fixture comprises two lamp holders 1 and 2 which are alike in structure and are mounted in spaced relation to each other at opposite ends of a channel strip 3 which may be shaped in cross section as shown in Fig. 5. Attached to channel strip 3 and serving to close its open side is a reflector 4. Mounted on top of the channel strip is a ballast 5. Tubular lamps, for example fluorescent lamps of a known type, are indicated at 6, their end contact pins being indicated at 7. In each lamp holder is a starter 8, the starter for one lamp of the pair being in one holder and the starter for the other lamp of the pair being in the other holder.

Each holder comprises a shallow rectangular casing having a bottom wall 9, side walls 10 and 11, an end wall 12, a top wall 13 and an open front closed by a cover plate 14. At its top, the casing is provided with walls which define an extension 15 of less length than the main body of the casing, thus providing shoulders 16 on each side of the extension. Attached to extension 15 are corner brackets 17 having suitable openings 18 through which extend bolts 19 (Fig. 2) for fastening the holders to channel strip 3. Extension 15 is of a length to fit nicely between the inturned inner edges of the channel strip as shown clearly in Fig. 2 and 5. Fixed to end wall 12 and projecting forwardly toward the open side of the casing are two pairs of diagonally spaced posts 20 and 21 shaped to provide shoulders at their free ends against which cover plate 14 rests. The ends of the posts beyond the shoulders project through openings in the cover plate and are adapted to

receive screws 22 for fastening the cover plate in position against the shoulders on posts 20 and 21. To support the edges of the cover plate, the casing walls are provided with struck-in ears 23 to provide shoulders against which the plate edges 16 are held by the screws. In cover plate 14 are two round openings 24 of a diameter slightly greater than that of the tubular lamp with which the holder is to be used and in line with each opening is a cover disk 25. The cover disks 25 are supported on the pairs of posts 20 and 21, the disks being provided with spaced openings 26 through which the posts pass with a loose fit. In each cover disk 25 is a pair of openings 27 sized and spaced to receive a pair of lamp pins 7. Positioned in casing extension 15 is a contact carrying block 28 of insulating material. It is supported between the top wall of extension 15 and struck-in ears 29 on the side walls of the extension and is held in place by cover plate 14, the upper edge of which partly overlaps block 28 as shown particularly in Fig. 6, block 28 being provided with a transversely extending recess in which the upper edge of the cover plate rests, the recess being of a depth such that the outer surface of the cover plate is flush with the outer surface of the block.

Mounted on insulating block 28 are two pairs of lamp pins engaging contacts 30 and 31 and a pair of starter contacts 32. They are fastened to the block by suitable screws 33. The screws 33 that hold in place contacts 30, one of the contacts 31 and one of the contacts 32 also hold in place angle strips 34 which are located in recesses in the block; these angle strips are electrically connected to the respective contacts, and are provided with binding screws 35 for fastening electric wires to the contacts. The other of the contacts 31 and 32 are connected together by a metal strap 36 held in place by the corresponding screws 33. Contacts 30 and 31 are in the form of spring strips having one end attached to the block and the other end free. In the block are suitably positioned holes 37 through which the ends of conductors may be passed to positions under the heads of the binding screws 35 to be clamped by

such screws. The free ends of the pairs of contact strips 30, 31 terminate in line with the openings 27 in the cover disks 25, the free ends engaging the cover disks to hold them against the back surface of cover plate 14. The free ends of contact strips 32 are bent at right angles and are positioned in line with curved keyhole slots 38 in an insulating disk 39 which is fastened over the end of a tubular casing 40 fixed to bottom wall 9 of the casing. As shown clearly at the left hand side of Fig. 2, casing 40 is positioned in line with an opening in wall 9 and is provided with wings 41 which may be welded or otherwise suitably attached to wall 12. Insulating disk 39 is held in position by means of inturned ears on casing 40 and wings 41 as shown particularly in Fig. 4. Casing 40 is of a size to receive a starter 8. The starter is positioned in the casing with its pins projecting through the keyhole slots into engagement with the ends of the contact strips 32.

The ends of the channel strip 3 are closed by end plates 42 held in place by screws 43, as shown clearly in Fig. 6.

The reflector is fastened to the channel strip by cross straps 44 (Figs. 3 and 5) held in place by studs 46 which thread into tapped openings in U-shaped brackets 47. Straps 44 are provided with offset portions 48 at their centers which seat in openings in the reflector to center the reflector with respect to the channel strip.

Conductors for wiring the fixture are indicated at 50. In the present instance, there are three conductors extending from the ballast to each lamp holder and one conductor which extends from one lamp holder to the other. They extend along the channel strip and may be held in the channel of the strip by suitable transversely extending rods 51 which extend beneath the wires and have their ends held by the channel strip walls as shown clearly in Fig. 2.

For convenience in wiring, the ends of conductors 50 are clamped, molded or otherwise held between two strips 52 fastened together by screws 53 and are spaced to correspond to the spacing of holes 37 in block 28. Thus all the conductor ends may be at one time inserted through the openings 37 to position beneath the heads of screws 35 after which the screws may be tightened, the heads of the screws being accessible through an opening 54 in the top wall of extension 15. This eliminates the possibility of wiring the fixture incorrectly.

The ballast 5 is attached to the channel strip by bolts 55, the lead wires 50 from it being brought down through openings 56 in the top wall of the channel strip.

In assembling a lighting fixture, a channel strip 3 of the desired length is provided and the ballast 5, having the ends of its lead wires clamped between the strips 52 (a thing which may be with advantage done at the factory), is attached to it by bolts 55. Next, the strips 52 with the attached lead wires may be passed endwise through openings 56 to the inside of the channel; and following this the bared ends of the lead wires may be inserted through the openings 37 under the heads of the several binding screws 35, after which the screws may be tightened down on the bared ends of the conductors. After the conductors have been attached to the two lamp holders, the lamp holders may then be fastened at the two ends of the channel strip by means of the bolts 19. Following this, the reflector may be fastened in position by means of the straps

44 and the end plates 42 for the channel strip put in place.

The lamp holder is simple in structure and is capable of being manufactured at low cost. The several contacts 30, 31 and 32 can be quickly and easily assembled on the block 28 after which the block is pushed into position in extension 15 between the top wall of the extension and the struck-in ears 29. By this arrangement, the block is assembled in the casing without the use of screws. After the block is positioned in the casing, the cover disks 25 are positioned over the pairs of posts 20 and 21 in engagement with the ends of contact strips 30 and 31 after which the cover plate 14 may be put in position and fastened by the screws 22. The spring contact strips 30 and 31 serve normally to hold the cover disks 25 in engagement with the inner surface of cover plate 14 as shown clearly at the lower right hand portion of Fig. 3.

To insert a lamp into the fixture, the pins at one end of the lamp are passed through the holes 27 of the one cover disk into engagement with the ends of the contact strips after which the end 25 of the lamp is pushed through the opening 24 in the cover plate against the action of the spring contact strips until the other end of the lamp can be brought into line with the corresponding cover disk of the other lamp holder. This is illustrated in the lower half of Fig. 3 where it will be seen that the left hand end of the lamp extends through the opening 24 and has pushed cover plate 25 back away from the opening, the lamp pins 7 being in engagement with the contact strips. The lamp having been brought to the position shown in the lower half of Fig. 3, it is then permitted to move toward the right to permit the pins 7 at the right hand end of the lamp to pass through the openings 27 in the adjacent cover disk into engagement with the spring contact strips of the other lamp holder. The lamp then positions itself between the two sets of contact strips, the location of the end of the lamp when fully positioned in the fixture being shown at the upper left hand portion of Fig. 3. When mounted in the fixture, the lamp is held firmly in position by reason of the pins 7 being located in the openings in the cover disks 25. Also, it will be noted that the space between the two lamp holders is less than the lamp length so that the lamp ends lie within openings 24. As a result, the lamp is not likely to become detached from the fixture accidentally due to vibration, for example, and fall out of the fixture. The lamp may be easily removed by shifting it axially in one direction or the other to bring the pins 7 out of contact with the lamp holder at the one end after which such end of the lamp may be moved beyond the lamp holder and removed from the other lamp holder by an axial movement. The starters 8 are positioned in the casings 40 with their contact pins in engagement with the ends of contacts 32. They extend part way into the lamp holder casing, projecting sufficiently far outside so that they are readily accessible for replacement.

In certain installations where fluorescent lamps are started by a higher starting voltage, a starter 70 for a lamp is not needed. In such instances, it is desirable to short circuit the lamp pin contacts after the lamp is in position. An arrangement for performing this function is shown in Fig. 7 wherein an additional spring contact strip 58 is provided in connection with each of the pairs of

contacts 30 and 31 so that when a lamp is positioned in the lamp holders, it connects the two spring contact strips together. Contact strip 58 is fastened at its inner end directly to one of the pair of contacts and projects diagonally across the other of the pair, the arrangement being such that when the pair of contacts is engaged by the pins of a tubular lamp and moved outwardly, the contact of the pair to which contact strip 58 is not connected is brought into engagement with contact strip 58 to connect together the contact strips of the pair.

What we claim as new and desire to secure by Letters Patent of the United States is:

1. A lamp holder comprising, in combination, a housing having a top wall formed with an extension and end walls provided with shoulders extending outwardly from opposite ends of said extension, a front wall of said housing being provided with spaced openings of a diameter to receive a tubular lamp, said openings being located in the area formed by said shoulders, cover disks closing said openings, said disks being provided with a pair of holes for receiving the contact pins of a lamp and being mounted for movement inwardly from said openings, a block of insulating material forming a terminal means located in said extension, spaced pairs of contact members carried by said terminal block, the individual contacts of each pair extending downwardly within the housing to points in line with the holes in the corresponding cover disks for engaging the lamp contact pins and terminal means carried by said insulating block for making electrical connections with the contact members.

2. A lamp holder comprising, in combination, a housing having a top wall formed with an extension, a front wall of said housing being provided with spaced openings of a diameter to receive a tubular lamp, cover disks closing said openings, each of said disks being provided with a pair of holes for receiving the contact pins of a lamp, said disks being slidably mounted for movement inwardly from said openings, a block of insulating material forming a terminal plate located in said extension, contact members carried by said terminal plate extending downwardly within the housing to points in line with the holes in the corresponding cover disks for engaging and making an electrical connection with the lamp contact pins, one face of said terminal plate being located substantially in the plane of the front wall of the housing and being provided with openings for receiving conductors for making electrical connections with said contact members, and means carried by said terminal plate for securing the conductors to said contact members.

3. A lamp holder comprising, in combination, a housing having a top wall formed with an extension, a front wall of said housing being provided with spaced openings of a diameter to receive a tubular lamp, cover disks closing said openings, each of said disks being provided with at least one hole for receiving the contact pin of

a lamp, said disks being slidably mounted for movement inwardly from said openings, a terminal plate of insulating material located in said extension, contact members carried by said terminal plate, said contact members extending away from the plate within the housing to points in line with the hole in the corresponding cover disks for engaging and making an electrical connection with the contact pin of a lamp, the face of said terminal plate adjacent the front wall of said housing being provided with openings for receiving conductors for making electrical connections with said contact members, and screw means carried by said terminal plate for securing the conductors to said contact members, the aforementioned top wall of said housing being provided with an opening to render said screws accessible.

4. A lamp holder comprising, in combination, a housing, a front wall of said housing being provided with spaced openings for receiving tubular lamps, cover disks overlying said openings, each of said disks being provided with holes for receiving the contact pins of a lamp and being movable inwardly from said front wall upon insertion of a lamp in the holder, a terminal plate of insulating material located in said housing between the contact disks, contact members carried by said terminal plate and extending away from the plate to points in line with the holes of corresponding cover disks for making electrical connections with the lamp contact pins, the bottom wall of said housing being provided with an opening therein, a casing within said housing located between the cover disks in line with said bottom opening to form a well for receiving a starting switch, and contact blades carried by said terminal plate and extending into alignment with said well to form socket contacts for the starter.

5. A lamp holder comprising, in combination, a housing having at top wall formed with an extension, a front wall of said housing being provided with spaced openings for receiving tubular lamps, cover disks overlying said openings, each of said disks being provided with holes for receiving the contact pins of a lamp, said disks being movable inwardly from said front wall upon insertion of a lamp in the holder, a terminal plate of insulating material located in said extension, flexible contact blades carried by said plate and extending away from the plate to points in line with the holes in the corresponding cover disks for making electrical connections with the lamp contact pins, the bottom wall of said housing being provided with an opening therein, socket means in said housing located between the cover disks and in line with said opening for receiving a starting switch inserted through said opening, and contact members carried by said terminal plate and extending into engagement with said socket means for making an electrical connection with the starting switch.
